UNITED STATES PATENT OFFICE

NORMAN H. SAUNDERS, OF HOMEWOOD, AND CLARENCE E. LOMAX, OF OAK PARK, ILLINOIS, ASSIGNEES TO RESERVE HOLDING COMPANY, OF CHICAGO, ILLINOIS, A CORPORATION OF DELAWARE

TELEPHONE SYSTEM

Application filed November 25, 1929. Serial No. 409,451.

The present invention relates to the telephone systems in general, but is concerned more particularly with an automatic telephone system for giving service to rather thinly populated rural districts; and the main object is the provision of an efficient and economical automatic switchboard of the so-called lineswitch-connecting type for giving party-line service to rural lines.

10 Lineswitch-connecting switchboards, it may be explained, are used in small systems of not more than one hundred lines. In such a switchboard, a single connector is associated with all of the local trunk lines and is, therefore, taken into use when any trunk line is seized and it is operated to make connection with a desired line and to signal the called subscriber on the line, after which the lineswitch on the called line is operated to 15 connect the called line with the same local trunk with which the calling line is connected, and the local trunk is disconnected from the connector, leaving the connector free for use in connection with the other 20 local trunks. The lineswitch-connecting systems heretofore known have been developed for the most part for use in connection with private automatic exchanges, and for that reason are not particularly suitable for 25 use in connection with public exchange systems. It is, therefore, an object of the invention to revise the lineswitch-connecting switchboard and render it suitable for use in small public exchanges, called community 30 automatic exchanges.

One object of the invention is to provide means for signalling the desired one of a plurality of subscribers on a party line.

Another object is to provide means for giving the calling subscriber a distinctive tone in case he calls an unassigned number and thereby causes the connector to connect with vacant line-terminals.

Another object is to provide a connector suitable for use in a lineswitch-connecting system wherein the lines are of the so-called local-battery, simplex-dialling type.

It is a further object to make such changes and alterations in the connector, consistent with efficiency and economy, as will follow

from the altered character of the subscribers' lines.

A further object is the production of new and improved line equipment which will lessen the number of trunks taken up by defective, partially-grounded lines. This is particularly advantageous in certain times of the year when storms or other natural agents do much damage to long open-wire lines.

It is a further object to put the improved line equipment into the circuit of a plunger lineswitch such as is used in the lineswitch-connecting switchboard and to so arrange the lineswitch that it does not operate responsive to the removal of the receiver (and consequent grounding of the line) until ringing current is projected over the line by the turning of the usual hand generator.

The various objects and features of the invention will be better understood upon a further perusal of the specification in connection with the accompanying drawings comprising Figs. 1 to 4.

The drawings show by means of the usual circuit diagrams a sufficient amount of equipment in a community automatic exchange embodying the features of the invention to enable the invention to be understood.

General description

Fig. 1 shows three lines incoming to a lineswitch-connecting switchboard. The line SL is a subscriber's party line; the line TL1 is a trunk line connecting the community automatic exchange with a distant manual exchange, and the trunk line TL2 is a second trunk line between the two exchanges.

At the automatic switchboard, the three lines above mentioned terminate in the lineswitches LS1, LS2, and LS3, respectively. These lineswitches are of the usual plunger type, mechanically, and they, together with the other lineswitches of the switchboard, are controlled by the master switch MS, Fig. 3. This master switch is of the usual type, mechanically, and it has its circuits suitably revised to enable it to operate in the desired manner.

The lineswitches, of which three are shown

in Fig. 1, have common access to ten local trunks, of which the local trunk LT10 is shown in Fig. 1. Each of these local trunks is normally connected with the connector C of Fig. 2 with the result that a seizure of any trunk results in the seizure of the connector. Mechanically, the connector C is a two motion switch of the usual step-by-step type having its bank contacts arranged in ten horizontal rows or levels. Auxiliary to the connector C, there is a code selector CS, arranged to respond to a single digit, for which reason it has a rotary motion only.

The apparatus shown in Fig. 4 is auxiliary to the connector of Fig. 2 and includes a ringing interrupter RI; the dial-tone buzzer DT; the several relays shown along the bottom of the sheet; and the auxiliary switch AS. The switch AS is a switch having a continuous rotary motion and it has sixteen positions. The position in which the switch normally stands is called position 1. The positions in which the various cam springs such as 403, 404, etc. engage their cooperating contacts are indicated adjacent to the cams. For example, cam 403 engages its contact continuously in positions 2 to 16, while cam 404 engages its associated contact in position 1 only.

The equipment shown below the dotted line in Fig. 3 is power and supervisory equipment, collectively designated as power equipment and given the reference character PE.

General description of operation

The general operation of the system will now be outlined briefly. When a call is made, for example over the substation S1 on the party line SL, the receiver is removed, grounding the line through the two windings of the ringer R, but no current flows over the line because of the circuit connections at the lineswitch LS1. The hand generator HG is next operated and causes the lineswitch LS1 to operate in a manner to be described hereinafter and to lock itself over the subscriber's line. By operation of the lineswitch LS1, the local trunk LT10 is seized, because the master switch shown in Fig. 5 is standing on the tenth local trunk at this time. The trunk LT10 is connected to the connector C of Fig. 2, through contacts of the trunk relay 124, with the result that the connector C is taken into use. When this happens, the auxiliary switch AS starts to operate under the control of the interrupter comprising relays 412 and 413, so as to release the connector at the end of a predetermined time in case the dialling is not completed.

The subscriber dials the two digits assigned to the desired line, causing the connector C to be operated vertically and then in a rotary movement, after which the subscriber dials the code digit assigned to the desired station, causing the code selector CS to be operated.

As soon as the code selector has been op-

erated, the auxiliary switch AS is returned to its normal position and reoperates under the control of the interrupter to control the code ringing operation.

When the called subscriber responds by removing his receiver, the connector is freed by the operation of relay 124, and the line-switch on the called line is caused to plunge and take the same local trunk taken by the lineswitch of the calling line.

In case the called subscriber does not respond within a very short time after the ringing operation is completed, the operation of the auxiliary switch AS Fig. 4 brings about the above operation.

Following the connection of the two lines together by way of the local trunk LT10, the master switch MS operates (having been maintained in the same position while the call was being put through) to preselect another of the local trunks. The remaining line switches are prevented from operating responsive to control over their respective lines until the initiated call has been put through and a new trunk has been preselected.

Detailed description; call from substation S1 to the manual exchange

The system having been explained generally, a detailed explanation will now be given. For this purpose it will be assumed that the subscriber at substation S1 desires to converse with a subscriber who must be reached by way of the manual exchange, to which connections are extended over one of the trunk lines TL1 and TL2. The connector number of the manual exchange is O1, and the digit 1 is added to this number in order to operate the code switch to signal the operator. Accordingly, the complete number is O11.

When the receiver is removed at substation S1, a talking bridge is placed across the conductors of the line at contact 8; the transmitter T is connected in the local-battery circuit with the primary winding of the induction coil 102 at contact 9; and at the contact 7 a ground connection is made to the two conductors of the line through the contacts 105 of the calling device CD and the coils of the ringer R. Nothing happens for the time being as the result of this ground connection on account of the fact that the line is devoid of battery potential at the exchange.

In order to bring about the operation of the line switch LS1 to initiate the call, the subscriber turns his hand generator HG, thereby, projecting ringing current over his line to the exchange. The presence of condenser 104 in the talking bridge limits the flow of ringing current therethrough so that a sufficient amount is sent to the exchange to bring about the desired result.

At the switchboard, relay 106, whose upper winding is bridged across the conductors

of the subscriber's line through the contacts of the bridge-cut-off arm 108, operates in response to the ringing current. Upon operating, relay 106 first closes its contact marked X, thereby closing a locking circuit for relay 106 over the two conductors of the line in parallel, to ground through the switch-hook contact 7. Upon operating further, relay 106 short-circuits its upper winding so as to render the relay slow-releasing.

As a further result of its operation, relay 106 closes a circuit from the grounded, chain conductor 133 for the lower winding (the pull-down winding) of the lineswitch magnet 107. When this winding is energized, the core is magnetized sufficiently to operate the plunger arm 109 in addition to the bridge-cut-off arm 108. The bridge-cut-off arm 108, at its associated spring contacts, disconnects line relay 106 from the subscriber's line, but the relay remains operated for the time being owing to the slow-action effect of its short-circuited upper winding. The plunger arm 109 operates the springs 110—113 of the lineswitch, extending the connection through to the preselected local trunk LT10. The conductors of the subscriber's line are now extended by way of the talking conductors 121 and 123 of the local trunk LT10 and the common conductors 127 and 131 to the connector C, Fig. 2. Line relay 202 of the connector C now operates through the two windings on the impedance coil 201 in parallel, and over the calling line to ground at the switch-hook contact 7.

Upon operating, line relay 202 closes a circuit for release relay 203 through the series relay 211. Relay 211 does not operate at this time owing to the fact that it is shunted by the rotary magnet 217, which is connected in parallel with it through the middle lower armature, normal, of relay 204 and armature 224, normal. Magnet 217 does not operate owing to the relatively high resistance of release relay 203.

Upon operating, relay 203 disconnects the test conductor 128 of the master switch MS, Fig. 3, from the start conductor 129 and connects it to ground, at armature 213, thereby closing a circuit over conductor 128 and through wiper 315 and over conductors 134 and 122 for the combined holding and cut-off winding (the upper winding) of magnet 107 of the lineswitch LS1. This circuit includes the spring 111 of the lineswitch and its associated contact. The current-flow through this winding is sufficient to maintain the bridge-cut-off armature 108 and the plunger arm 109 operated after relay 106 falls back and opens the circuit of the pull-down winding of the magnet, as it very shortly does.

As a further result of the operation of release relay 203 of the connector, the open-

chain conductor 130 is grounded at armature 214, operating the slow-acting open-chain relay 313 of the master switch and thereby removing ground potential from chain conductor 133. The removal of ground from conductor 133 opens the circuit of the lower winding of magnet 109 at this time whether the line 106 has fallen back or not, and it prevents the operation of further lineswitches.

As a further result of its operation, relay 203 closes a locking circuit for itself at its inner lower armature, thereby preparing the operating circuit for the magnets as will hereinafter appear, and at its upper armature closes a circuit through the off-normal contacts 215 for relay 204. Relay 204 operates and at its middle lower armature disconnects the rotary magnet 217 from in parallel with relay 211 and substitutes the vertical magnet 216. The circuits are now in readiness for the calling subscriber to start dialling.

As a further result of its energization, relay 203, at its lower armature, grounds the tone-start conductor 256 through the normally closed contacts controlled by armature 225 of switching relay 212, closing a circuit through cam 404 of the auxiliary switch AS in position 1 and through contacts of relay 415 for the tone-start relay 416. Upon operating, relay 416 closes a circuit for the magnets of the dial-tone buzzer DT through the associated resistance to battery. The operation of the buzzer causes a characteristic potential change on conductor 258, resulting in a flow of dial-tone current back to the calling line through the lower contacts of relays 208, 210, and 212 and through the condenser 271. The audible sound produced in the receiver at the calling telephone notifies the calling subscriber that he may now dial the desired number.

As a further result of the operation of relay 416, a point in the restoring circuit of the auxiliary switch AS is opened at the upper armature of the relay and a ground potential is extended over conductor 431 to the interrupter comprising relays 412 and 413. Relay 413 operates through the associated resistance and removes the short circuit from around relay 412, at the same time closing a circuit for the said relay 412. When relay 412 operates it short-circuits relay 413. Relay 413 falls back after a slight interval and opens the circuit of relay 412 and replaces the short circuit around its winding. When relay 412 falls back, relay 413 reoperates, this operation continuing as long as conductor 431 remains grounded. The copper collars placed on the upper ends of the relays 412 and 413 render the relays slightly slow to operate, having a steadyng effect upon the operation.

Each time relay 412 operates, it closes a circuit for the operating magnet 401 of the

auxiliary switch AS. Each time relay 412 falls back it opens the circuit of the operating magnet 401, allowing the magnet to deenergize and advance the switch to the next position. The interrupter comprising relays 412 and 413 is adjusted to operate at a rate which will allow sufficient time for the dialling of a complete number before the auxiliary switch AS completes its cycle and returns to position 1.

When the switch AS leaves position 1, contact 404 opens the initial circuit of relay 416, but relay 416 remains operated in a locking circuit from the grounded conductor 256 in series with relay 415. Relay 415, having been short circuited heretofore, now operates in series with relay 416 and prepares a cut-off circuit to be subsequently described.

As a further result of the placing of ground potential on conductor 256, the differentially wound tone relay 414 operates in a buzzer-like manner, and sends a tone current directly over the vacant-tone conductor 255, and an interrupted tone through contacts of relay 412 to the busy-tone conductor 251. In connection with the operation of relay 414, it may be pointed out the upper and lower windings are reversed with the respect to one another and that, upon operating, the relay connects the lower winding in parallel with the upper winding, causing a neutralization of effect and a consequent retraction of the armature of the relay. This operation continues at a rather rapid rate and gives rise to a characteristic tone current.

In case the calling subscriber does not dial the number and thereby cause the connector to remove ground potential from the tone-start conductor 256, a cut-off circuit is completed from grounded conductor 256, and through cam 404 and the lower armature, operated, of relay 414, to conductor 254, when the auxiliary switch AS again reaches position 1. Over this cut-off circuit, relay 124 of the local trunk LT10 is operated to cut off the connector and return it to normal use in a manner to be subsequently pointed out.

It will now be assumed that the calling subscriber, upon hearing the dial-tone transmitted back to his substation over conductor 131 of the connector and over the lower talking conductor of his line, as above pointed out, dials the three digits 0, 1, and 1 without undue delay.

When the first digit 0 is dialled, the circuit of line relay 202 of the connector C, Fig. 2, is opened ten times at the contacts 105 of the calling device CD, upon the return of the calling device to normal. It will be noted that the off-normal springs 6 exclude the coils of the ringer R from the dialling circuit as long as the dial is off-normal.

Each time its circuit is opened, line relay 202 falls back and places a shunt around the winding of release relay 203, thereby closing

a circuit for the vertical magnet 216 through the grounded inner lower armature of the operated relay 203, contacts of line relay 202, and the middle lower armature, operated, of relay 204. Vertical magnet 216 operates each time this circuit is closed by the shunting of release relay 203, and the magnet restores each time the shunt is removed from around relay 203. Each time relay 203 is shunted, a direct circuit is closed for series relay 211 in parallel with vertical magnet 216. Relay 211 operates, and it is so designed and proportioned that it remains operated throughout the series of impulses due to the fact that it is in parallel with the vertical magnet and in series with release relay 203.

By the operation of the vertical magnet 216, the wipers A to E of the connector are raised step by step until they arrive opposite the tenth level of bank contacts. When relay 211 operates, it closes a locking circuit at its inner lower armature for relay 204 through the inner contacts of the said relay. This circuit is effective to maintain relay 204 operated after its initial circuit is opened at off-normal contacts 215 upon the first vertical step of the switch.

When relay 211 falls back at the end of the vertical movement, it opens the locking circuit of relay 204 at its inner lower armature. Relay 204 falls back and transfers the operating circuit from the vertical magnet 216 to the rotary magnet 217 at its middle lower armature.

When the switch is operated to the tenth level (as it now is), the "0"-level contacts 218 close, completing a circuit for the "0"-level relay 209. Relay 209 operates in preparation for a trunk-hunting operation on the tenth level.

When the second digit 1 is dialled, the single momentary deenergization of the line relay 202 results in the delivering of an impulse to the rotary magnet 217, and in the delivering of an impulse to the series relay 211. Series relay 211 again energizes, and rotary magnet 217 operates to rotate the wipers A to E onto the first set of bank contacts O1 in the tenth level. This set of bank contacts is shown in the upper right-hand portion of the drawing. Relay 211 disconnects the test wiper C from the lower winding of switching relay 212 and connects it instead to the winding of busy relay 210 so as to enable the busy relay to operate over wiper C in case the called line tests busy. Relay 211 also shunts the contacts of relays 208 and 210 at its lower armature so as to prevent a premature opening of the operating circuit in case either relay 208 or relay 210 should operate during the rotary movement.

Assuming that the trunk line TL1 of Fig. 1 is busy, there is a ground potential on the lead thereof, and, as a result, busy relay

210 operates as soon as the C wiper of the connector lands upon the *c* contact of set O1. As soon as the rotary magnet 217 deenergizes following this rotary step, relay 208 energizes from ground potential on the *c* conductor through the connection between contacts *c* and *d* of set O1, the D wiper of the connector, inner lower armature and working contact of relay 209, and the interrupter contacts of rotary magnet 217. Upon operating, relay 208 closes a locking circuit for itself at its inner upper contacts through the inner upper contacts of relay 209 and the interrupter contacts of rotary magnet 217. At its middle upper armature, relay 208 closes a circuit for rotary magnet 217, through the upper contacts of relay 209. Rotary magnet 217 reoperates and advances the wipers A to E of the connector into engagement with the bank-contact set O2, the second contact set in the tenth level. The bank-contact set O2 is the set associated with the trunk line TL2, Fig. 1.

The further operation depends upon whether the trunk line TL2 is busy or idle. In case this trunk line also is busy, the busy relay 210 remains energized over the C wiper of the connector, but relay 208 does not operate again owing to the fact that the *c* and *d* contacts of set O2 are not connected together. Accordingly, the wipers of the connector remain on the bank contact set O2 in spite of the busy condition of the trunk line TL2.

When the slow-acting series relay 211 falls back, as it does when the rotary movement ceases, it closes a locking circuit for busy relay 210 from ground by way of the upper armature of release relay 203, through the inner upper armature, operated of relay 210, and the normally-closed contacts controlled by the upper armature of relay 211. With relay 211 restored and relay 210 operated, the locking circuit of release relay 203 is opened and no further impulses can be delivered to the rotary magnet by subsequent deenergizations of the line relay when the next and last digit is dialled. The interrupted tone from the busy-tone lead 251 is connected through the lower armature of relay 210 and the lower armature of relay 212, and through the condenser 271 to the lower talking conductor 131 to notify the calling subscriber of the busy condition.

If the calling subscriber replaces his receiver immediately upon hearing the busy tone, the connector releases responsive to the falling back of the line relay when its circuit is opened at the substation. If he does not hang up immediately, the connector releases responsive to the operation of cut-off relay 124 responsive to auxiliary switch AS reaching position 1 after having been advanced through its other positions.

Assuming now that one of the trunk lines is found to be idle, the trunk line TL1 for

example, a connection is made to the trunk line by the energization of switching relay 212: Since the line is idle, busy relay 210 is not energized when the wipers come to rest, and a circuit is completed for the lower winding of relay 212 upon the falling back of series relay 211. This circuit is from ground through the upper contacts of the release relay 203, the inner upper armature, normal, of busy relay 210, upper contacts of relay 208, lower winding of relay 212, upper armature of relay 211, and the inner upper armature of relay 212 to wiper C. This circuit is completed to battery over the *c* contact and *c* lead of the contact set O1 and over the *c* lead of the lineswitch LS2 by way of the upper winding of the lineswitch magnet. When energized by means of its upper winding alone, the magnet is able to operate the cut-off armature, corresponding to the armature 108 of the lineswitch LS1, but is unable to operate its plunger arm, corresponding to arm 109 of the lineswitch LS1. Accordingly, the trunk line TL1 is cleared of attachments at the automatic switchboard.

In the connector, relay 212 energizes by means of its lower winding and closes a locking circuit for its upper winding at armature 221; at its inner upper armature it replaces the connection to the C wiper through the lower winding of the relay with a direct ground connection; at armature 224 it disconnects the operating conductor from rotary magnet 217 and extends it to the operating magnet 229 of the code selector CS.

When the calling subscriber dials the next digit 1, one impulse of current is delivered to the operating magnet 229 of the code selector CS, and the wipers 227 and 228 are advanced onto the first set of bank contacts. Series relay 211 is reoperated as before, and, when it falls back at the end of the digit, it closes a circuit for operating busy relay 210 at its inner lower armature through the off-normal contacts 226 of the code selector CS. When relay 210 operates with switching relay 212 operated, the ground potential is disconnected at armature 219 from the tone-start conductor 256 and is transferred to the interrupter-start conductor 252. Upon the removal of the ground potential from conductor 256, relays 415 and 416 fall back; tone relay 414 ceases operating; and the interrupter comprising relays 412 and 413 stops operating. In addition, a circuit is closed through contacts of relays 417 and 416, and through cam 403 (closed in positions 2 to 16), and the interrupter contacts 402 of stepping magnet 401, for stepping relay 411 of the auxiliary switch AS. Relay 411 operates and closes a circuit for magnet 401, whereupon magnet 401 operates and opens the circuit of the stepping relay. The stepping relay falls back and opens the circuit of the operating magnet, whereupon the operating

120
125
130

magnet falls back and again connects up the stepping relay. This operation continues until the stepping-relay circuit is opened at cam 403 when the auxiliary switch leaves position 16 and goes into position 1.

When the auxiliary switch reaches position 1, a circuit is closed from the grounded interrupter-start conductor 252 for the interrupter-start relay 417 through cam 405 (closed in position 1). Relay 417 operates and locks itself to conductor 252 at its upper armature, and at its inner armature it opens a further point in the restoring circuit of the auxiliary switch and starts the interrupter comprising relays 412 and 413 to operating again.

At armature 424 a circuit is prepared for the ringing-control relays 418—422, and at armature 423 the operating circuit of the ringing-interrupter RI is closed. The ringing-interrupter magnet 410 is differentially wound, and the interrupter accordingly operates in a vibratory manner, as it connects up its second winding in opposition to the first each time the vibratory spring 411 thereof is attracted. The lower contacts of the pendulum 411 control the current-supply to the primary winding of the associated transformer, with the result that an alternating ringing current is produced in the secondary winding and is delivered to the connector over conductor 257.

When the auxiliary switch AS reaches position 2, a circuit is closed through armature 424 and cam 406 for relay 418, through contacts of relay 419. Relay 418 operates and locks itself in series with relay 419 through contacts of relay 421. Relay 419 does not operate for the time being owing to the fact that it is short-circuited by the initial circuit of relay 418. Relay 418 also places a ground potential at its upper contacts, and through contacts of relay 420, on the reversing conductor 253, preparatory to operating the reversing relay 206 of the connector. A ground potential also extends through contacts of relay 419 to the pick-up conductor 259, operating pick-up relay 205 of the connector through armature 222 of relay 212, and the middle upper armature of relay 210. Pick-up relay 205 locks itself at its upper armature through contacts of the restored relay 204 and contacts of the operated relay 203. Relay 205 also connects up the reversing relay 206 to the grounded reversing conductor 253 at its inner armature, whereupon the reversing relay operates and connects the ringing relay 207 to the upper wiper 227 of the code switch CS through the lower contacts of the pick-up relay 205. The reversing relay is provided for the purpose of shifting the connection back to wiper 228 of the code switch CS after one code digit has been sent out, so as to permit the second code digit to be sent out under the control

of wiper 228 in case the setting of the code switch is in accordance with a code-selecting digit to which two code digits are assigned.

As soon as the auxiliary switch AS leaves position 2, the initial circuit of relay 418 is opened whereupon relay 419 operates in series with relay 418, and removes ground from the pick-up conductor 259.

It will be noted that conductor 260 is grounded by cam 409 in positions 7 and 11; that conductor 261 is grounded by cam 408 in positions 5 and 7, and in positions 11 and 13; and that conductor 262 is grounded by cam 407 in positions 3, 5, and 7, and in positions 11, 13, and 15. Since the code selector CS is standing on the first set of contacts, and since wiper 227 is connected up by the reversing relay 206 and the pick-up relay 205, to the ringing relay 207, the ringing relay 207 operates over conductor 260 when the cam 409 closes in position 7, causing one application of ringing current to be made to the trunk line TL1 from the generator lead 257, through the inner armature of the ringing relay 207, and over the A wiper, to the *a* lead of the trunk line TL1, a return circuit being provided over the *e* lead of trunk line TL1, and through the E wiper of the connector to ground at the lower armature of relay 207.

When the switch AS reaches position 9, a circuit is closed at cam 406 through the lower armature of the operated relay 419 for relay 420, and this circuit remains closed until the auxiliary switch passes through position 15. Relay 420 now operates and locks itself through relay 421, which relay is short-circuited for the time being, and at its upper armature relay 420 removes ground potential from the reversing conductor 253, whereupon reversing relay 206 falls back and shifts ringing relay 207 from in connection with wiper 227 into connection with wiper 228. Accordingly, the application of ringing current to the line (if any) after the auxiliary switch has reached position 9 is under the control of wiper 228 of the code switch. In this case, since wiper 228 is standing on the first contact in its bank, which contact is not connected to any of the conductors 250—252, there is no second application of ringing current to the trunk line TL1. It will be understood, of course, that when the code-selecting digit is anything above 3, a second code ringing digit is sent during the passage of the auxiliary switch AS through positions 11—15.

It will be noted that the distant end of the trunk line TL1 terminates in the jack J1, with which is associated the drop D1. The drop D1 responds to the ringing current and displays the usual signal to the operator to attract her attention to the call. If the operator responds immediately by inserting the plug of a cord circuit (not shown) a circuit is completed from ground, through the cord

circuit, over the two sides of the line TL1 in parallel, and over the *a* and *e* leads of the line to the contact set O1, Fig. 2, and thence to battery through the A and E wipers of the 5 connector by way of the back contacts of the armatures of relay 207 and the combined change-over and ring-cut-off relay 204. In this case, relay 204 reoperates, and at this time places ground potential on conductor 10 126 at its upper armature, because the working contact of the upper armature is grounded through contacts of the operated relays 203 and 212. The placing of ground potential on conductor 126 results in an operation 15 to be described subsequently.

In the present case it will be assumed that the operator does not respond immediately and that the relay 204 is not operated as above described. In this case, the operation of the 20 auxiliary switch AS continues, following the application of ringing current in position 7, and the opening of the circuit of reversing relay 206 by the operation of relay 420 in position 9, until position 15 is reached, whereupon the initial circuit of relay 420 is opened 25 at cam 406. When this occurs, relay 421 operates in series with relay 420 through the lower contacts of the latter relay, and through contacts of relay 422. Upon operating, relay 30 421 opens the circuit of relays 418 and 419 at the resting contact of its armature, and it closes a circuit for relay 422 through the associated resistance, at the same time removing the normal shunt from around the winding 35 of relay 422. Relay 422 operates and opens the circuit of relay 421, whereupon relays 420 and 421 fall back, and relay 421 opens the circuit of relay 422, at the same time replacing the shunt around the winding of relay 422 so as to render the relay slow in releasing. 40 Relay 422, shortly falls back and again closes a point in the circuit of relays 420 and 421 but these relays do not reoperate on account of the fact that relay 420, upon falling back, 45 opens a point in the circuit of the two relays, in series.

During the time that relay 422 is operated, a ground potential is placed on conductor 254, and is extended over conductor 126, wiper 316, 50 tenth contact in the bank of wiper 316, conductor 135, and the normally-closed contacts controlled by the upper armature of relay 124, to relay 124. Relay 124 thereupon operates and locks itself to ground over the line 55 of the calling subscriber and conductor 121, at the same time opening the initial circuit over conductor 135, and, in addition, disconnecting conductor 121 from the corresponding conductor 127 extending to the connector C. 60 At its lower armature, relay 124 disconnects conductor 123 from the corresponding conductor 131 extending to the connector, and connects it to the impedance coil 125. At its inner upper armature, relay 124 places a 65 ground potential on release trunk conductor

122 so as to provide a holding circuit for the established connection after the ground potential is removed from the branch conductor 134, as it will be shortly.

As a further result of the application of ground potential to conductor 126, a pull-down circuit is closed for the lower winding of the magnet of lineswitch LS2 by way of the upper contacts of relays 210 and 212 of the connector, and over the B wiper and corresponding contacts in set O1, and the *b* lead of the lineswitch LS2. When this circuit is closed, the lineswitch LS2 operates and connects the trunk line TL1 with the local trunk LT10. The upper winding of the lineswitch magnet now receives current from the grounded release trunk conductor 122 so as to maintain the lineswitch operated and the line relay thereof disconnected after the circuit for the lower winding has been opened. 80

When the relay 422 falls back responsive to the deenergization of relay 421, it opens the initial circuit of the pull-down winding of the magnet of lineswitch LS2, leaving the lineswitch held operated by the upper wind- 90

ing. As soon as the operator responds by inserting the plug (not shown) of a cord circuit into the jack J1, she may converse with the subscriber at substation S1 and complete the 95 connection to the desired line.

When conductors 121 and 123 are disconnected from conductors 127 and 131, by relay 124, Fig. 2, line relay 202 falls back and short circuits release relay 203, at the same time 100 open-circuiting the relay. The operating magnet 229, to which the operating circuit has been extended, is not operated now because ground potential has been removed from the lower armature of release relay 203 105 at the inner lower armature of busy relay 210. After an interval, release relay 203 falls back, and at its lower armature removes ground potential from the interrupter-start conductor 252, whereupon the interrupter 110 start relay 417, Fig. 4, falls back and stops the operation of the associated interrupting apparatus, and closes the previously-dis- 115 cussed restoring circuit for the auxiliary switch through the upper contacts of relays 416 and 417 and the cam 403, closed in positions 2 to 16. As a result, the auxiliary switch is restored immediately to position 1.

As a further result of its deenergization, 120 relay 203, at its upper armature, opens the locking circuit of relays 205, 210, and 212. Relays 205 and 212 fall back, but relay 210 is maintained operated for the time being by its lower winding. Relay 209 falls back responsive to the opening of its circuit at the 125 lower armature of relay 203.

At its lower armature, relay 203 closes a circuit through off-normal contacts 232 for the release magnet 231 of the connector, and it closes a parallel circuit through armature 130

220 of relay 210 for release magnet 230 of the code switch CS. When the code switch CS reaches its normal position responsive to the energization of release magnet 230, relay 5 210 falls back because its circuit is opened at off-normal contacts 226, and it opens the circuit of release magnet 230 at armature 220.

When the connector C is restored to normal position by the action of release magnet 231, 10 the circuit of magnet 231 is opened at off-normal contacts 232. The connector, together with the apparatus associated therewith in Figs. 2 and 4, is now in normal condition.

As a further result of its deenergization, 15 release relay 203 removes ground from the open-chain conductor 130 at armature 214, thereby opening the circuit of the slow-acting open-chain relay 313; at armature 213 it disconnects conductor 128 from the local ground 20 potential and connects conductor 128 to start conductor 129. Start relay 312 of the master switch MS now energizes over conductor 134 (grounded at contacts of relay 124), through the tenth contact in its bank and wiper 315, conductor 128, armature 213, normal, and conductor 129. Upon operating, start relay 313 at its inner armature closes a holding circuit for the open-chain relay 313 from ground through the low-resistance right- 30 hand winding of supervisory relay 317 before the said open-chain relay has had time to fall back; and, at its lower armature, relay 312 extends the ground potential from the right-hand winding of supervisory relay 317 to the locking magnet 311. Magnet 311 35 operates and unlocks the associated locking segment, allowing the spring 304 to drive the master switch MS in a counter-clockwise direction and line up the plungers (not shown) of the unoperated lineswitches opposite an idle trunk. A ground potential is encountered by wiper 315 on each bank contact corresponding to a busy trunk, so that start relay 312 remains operated until an idle 40 trunk is reached, whereupon the start relay falls back and opens the circuit of the open-chain relay 313 and the circuit of magnet 311. The locking magnet 311 thereupon falls back and again locks the locking segment of the 45 master switch. Relay 313 now falls back; ground potential is restored to the chain conductor 133; and the apparatus is in readiness to receive and dispose of another call.

During conversation, holding current flows 50 over the calling line SL and over the trunk line TL1, in parallel, so that relay 124 is maintained energized until the plug (not shown) of the cord circuit is removed from the jack J2 of the trunk line, and until the receiver 55 is replaced at substation S1. When this occurs, the current flow through relay 124 and the impedance coil 125 ceases, and relay 124 falls back, again connecting conductors 121 and 123 with the common conductors 127 and 60 131, and removing ground from release-trunk 65

conductor 122. This latter operation opens the holding circuit of the upper windings of the magnets of the lineswitches LS1 and LS2, whereupon both line switches restore to the position shown in the drawings. 70

From the foregoing explanation, it is thought that it will be understood how any desired connection may be set up, such as for example from one local line to another local line, or from the operator's switchboard over one of the trunk lines to a local line. It may be pointed out that when a local line is called the "O"-level contacts 218 are not operated, and that the switch-over relay 209 is, therefore, not operated to give the connector an automatic hunting movement. Accordingly, when a local line is busy, the busy tone is returned by the action of relay 210, and there is no further advance of the connector wipers, as is the case when the operator is called and the trunk line TL1 is busy, as hereinbefore described. 80

Call to vacant line terminals

It is assumed that the terminal set 92, 90 shown in the upper right-hand corner of Fig. 2 (with which the wipers of the connector are brought into engagement when the first two digits of a number are 9 and 2), is not connected to a subscriber's line. Accordingly, the d contact in this terminal set is connected to ground, as shown, so that relay 208 operates over wiper D of the connector and through contacts of relay 209 when the wipers land on contact set 92. At its lower 100 armature, relay 208 breaks the connection with dial-tone conductor 258 and connects up the vacant-tone conductor 255. The continuous distinctive tone placed on conductor 255 by the previously-described operation of the tone relay 414 informs the calling subscriber that no line is connected to the called terminals. 105

Master-switch operation

For the purpose of completeness, further description will now be given of the operation of the master switch MS, Fig. 3. It was pointed out hereinbefore how the master switch responds to an energization of the start relay upon the release of the connector, following a successful connection, resulting in an energization of the locking magnet 311 through the right-hand winding of the supervisory relay 317 to disengage the locking segment 303 and allow the assembly to be driven in a counter-clockwise direction by the spring 304 until an idle trunk is encountered, at which time the start relay falls back because relay 315 no longer encounters ground potential. The locking magnet 311 falls back at this time and catches and holds the locking segment 303 so that the master switch remains in association with the idle trunk. When the selecting operation has 110

taken place until the master switch has advanced to its limit in the counter-clockwise direction, and the wipers 315 and 316 are on the contacts of trunk 1, the finger 309 of the master switch presses the finger springs 302 into contact with each other, with the result that, in case the first trunk is busy and relay 312 accordingly remains energized (or in case it is idle at the time and becomes busy later), a circuit is closed through contacts of the start relay from the right-hand winding of supervisory relay 317, through the contacts 304, for the trip relay 305, whereupon relay 305 operates its springs 306 and 307 into engagement with the associated contacts, and the extension of spring 307 engages the latch 308 on the spring controlled by finger 310. Spring 307 closes an alternative circuit for the locking magnet 311, independent of the lower contacts of the start relay, so as to maintain the locking magnet energized and the locking segment free for the time being, and spring 306 closes a circuit from the right-hand winding of supervisory relay 317 for the solenoid 301. Solenoid 301 draws in the associated plunger, rotating the master-switch assembly in a clockwise direction to the position shown in the drawing. When this occurs, finger 310 engages the associated spring and moves it up, unlatching the spring 306 and allowing springs 306 and 307 to disengage their associated contacts. This opens the circuit of solenoid 301, and it opens the alternative circuit of the locking magnet 311, with the result that magnet 311 deenergizes, unless the start relay 312 is energized in this position of the master switch because of a busy condition of the tenth trunk. In case the tenth trunk line is idle, or when an idle trunk line is reached in case the tenth trunk is busy, the locking magnet falls back and engages the segment and holds the master switch on the idle trunk.

Supervisory apparatus

It is to be noted that the locking magnet 311 is always energized while the master switch is operating, and that it always closes a circuit for the two windings of the supervisory relay 317 in series so that the supervisory relay 317 is always energized during the operation of the master switch. As an extra precaution, the ground potential for operating the various relays and magnets of the master switch, with the exception of start relay 312 is obtained through the low-resistance right-hand winding of relay 317. The relay 317 closes a supervisory circuit through the master-switch signal-lamp 341 for the upper winding of relay 340. This relay is common to the master-switch signal circuits and the release signal circuits. Whenever this relay operates, either due to an operation of the master switch or to a releasing operation of the connector C of Fig. 2 (in

which latter case it operates in parallel with release magnet 231 through off-normal contacts 232 and over conductor 132 and through the release-signal lamp 342), it operates its armature preparatory to operating the slow-to-operate relay 339. The contact with which the armature of relay 340 engages is a weighted contact, and it vibrates a few seconds after being struck by the armature. Relay 339 is adjusted so as not to operate 70 while the weighted contact of the armature of relay 340 is vibrating. By this means, relay 339 does not operate in the case of a regular operation of the master switch or in the case of a regular release of the connector, but only in case the connector is stuck and fails to release, or the master switch continues to operate without finding an idle trunk. 80

When relay 339 operates, after the vibrating contact of relay 340 has come to rest with the armature in an energized condition (which occurs only during an abnormal condition), it connects the lower winding of relay 340 in parallel with the upper high-resistance winding of the relay so as to enable the lamp 341 (or 342, as the case may be) to become lighted. At its upper armature, relay 339 closes a circuit for the buzzer 338 so as to notify an attendant repairman in case he is present. It may be pointed out that the buzzer circuit is usually extended by means of an auxiliary trunk circuit (not shown) over one of the trunk lines so that an alarm is sounded in the manual exchange. 100

Current supply

The battery which supplies the current to the apparatus shown in the drawings is the battery B, shown in the lower-left-hand corner of Fig. 3. This battery supplies current through the fuses 333 and 334 and the ammeter AM to the bus-bars 335 and 336. The charging current is supplied to the battery B through the fuses 331 and 332. The connection from the charging source to the grounded terminal of battery B is through the ground bus-bar 336 (instead of directly to the lower terminal of the battery) so as to operate the ammeter AM either on charge or 110 discharge. 115

The voltmeter VM is bridged across the terminals 335 and 336 to show the voltage of the battery. 120

In case a fuse associated with bus-bar 335 blows, one of the special spring contacts thereof is forced into engagement with the bus-bar 337, closing a circuit from the battery bus-bar 335 over the bus-bar 337 and through the associated lamp to the alarm relay 339. 125

What is claimed is:

1. In a telephone system, a telephone line extending from a subscriber's substation to a telephone exchange, a line relay connected to said line in the telephone exchange, a 130

- source of current at the exchange, a source of current at the substation, means at the substation for preparing a circuit over the telephone line for said line relay, means for applying said source of current at the substation to the line to operate said relay, and means responsive to an operation of said relay for closing the prepared holding circuit for the relay over the subscriber's line from the source of current at the exchange.
2. In a telephone exchange system, a subscriber's line extending from a subscriber's substation to a telephone exchange, a line relay for said line in the telephone exchange, a source of current at the exchange and a source of current at the substation, and means for operating said relay from said source of current at the substation and for closing a locking circuit for the relay over the line from the source of current at the telephone exchange.
3. In a telephone exchange system, a subscriber's line extending from a subscriber's substation to a telephone exchange, a line relay for said line in the telephone exchange, a source of current at the exchange and a source of current at the substation, means for operating said relay from said source of current at the substation and for closing a locking circuit for the relay over the line from the source of current at the telephone exchange, a non-numerical switching device, and means for operating said device responsive to the operation of said line relay.
4. In an automatic telephone exchange system, a calling line, a called line, a current source on the calling line, a current source in the exchange, means in the exchange responsive to a current flow from the source on the calling line for setting up a current flow over the line from the current source in the exchange, means on the calling line for producing interruptions in the current flow from the source in the exchange, and an automatic switch in the exchange including a line relay directly responsive to said interruptions, said switch being responsive to said line relay to set up a connection between said lines.
5. In an automatic telephone system, automatic switching apparatus arranged to set up a connection from a calling line to a called line, a non-numerical switch arranged to effect a connection from a calling line to said automatic switching apparatus, a current-source on the calling line, a current-source in the exchange, circuit connections including a line relay in said non-numerical switch directly responsive to current-flow from the current-source on the calling line for operating said non-numerical switching apparatus, and means on the calling line for controlling the current-flow from the source at the exchange over the calling line for operating said automatic switching apparatus.
6. In a telephone exchange system, a subscriber's line entering the exchange, a line relay for said line at the exchange, a current source at the exchange and a current source on the line, circuit connections for operating said relay from the current source on the line over the two conductors of the line in series, and a locking circuit for said relay including the current source at the exchange, the two conductors of the calling line in parallel, and a separate return conductor.
7. In a telephone system, a line entering a telephone exchange, a current source in the exchange, a current source on the line, a line relay in the exchange, means for operating said line relay from the current source on the line and over the two conductors of the line in series, and circuit connections for maintaining said line relay operated over a circuit path from the source in the exchange, over one conductor of said line and a return conductor separate from the other conductor of said line.
8. In a party-line telephone system wherein lines terminate at the telephone exchange in individual lineswitches having access to a plurality of local trunk lines, an automatic switch common to said local trunk lines and having access to all of the said lines entering the exchange, means controlled over any calling one of said lines for operating the individual lineswitch to seize a local trunk line and for operating said automatic switch to effect a connection with a desired line, means individual to said automatic switch responsive to further control over the calling line for signalling the desired substation on a called party line, and means effective after the desired subscriber on the party line has been signalled for operating the lineswitch on the called line to connect with the same local trunk seized by the lineswitch on the calling line and for releasing said automatic switch.
9. In an automatic telephone system, an automatic switch arranged to be controlled over a calling line to make connection with a called line, a party selector associated with said automatic switch and arranged to be set under the control of the calling line in accordance with the desired station on the called line, a timing device associated with said automatic switch, means for operating said timing device to free said automatic switch in case it is held for a predetermined time without being fully operated, and means including said timing device and effective when the said automatic switch and the associated party selector are fully operated to place ringing current on the called line in accordance with the setting of said party selector.
10. In a telephone system, an automatic switch arranged to complete a connection from a calling line to a desired called line through one of its terminal sets, one terminal of each set not connected to a line having a special connection thereto, and means in said

switch controlled over said special connection when the switch is set on a vacant terminal set for informing the calling party of the fact.

11. In a telephone system, an automatic switch arranged to complete connections from a calling line to desired called lines through its terminal sets, one terminal of each set not connected to a line having a special connection thereto, and means in said switch controlled over said special connection for placing a distinctive tone on the calling line.

12. In combination, an automatic switch having a line incoming thereto, a line relay for said automatic switch having a line winding and a holding winding, said line winding being connected in circuit with said line, a current source, contacts on said line relay closed responsive to an energization of said relay by current-flow through said line and through the line winding of the relay, additional contacts on said relay closed when the relay is additionally energized by current-flow from said current source through the holding winding, said additional contacts being arranged to short-circuit said line winding, an operating circuit for said automatic switch, and still other contacts on said line relay for controlling said operating circuit.

13. In combination, an automatic switch, a line incoming to said switch, a line relay for said switch having a line winding and a locking winding, contacts on said relay effective when current flows over the line and through the line winding to close a circuit for the relay through its locking winding, operating contacts on said line relay for closing an operating circuit for the automatic switch, contacts on the automatic switch for disconnecting the line relay from the line and for opening its locking circuit, and additional contacts on said line relay for short-circuiting the line winding thereof so as to render the relay slow to release and thereby enable it to maintain the operating circuit of the switch closed for an interval.

14. In combination, an automatic switch having a release magnet, supervisory apparatus, means for operating said automatic switch to establish a desired connection, means effective thereafter for closing a circuit for said release magnet and for closing a circuit for said supervisory apparatus, said release magnet being responsive to the closure of its circuit to restore the switch to its normal position, off-normal contacts included in said release magnet circuit and opened responsive to said switch attaining its normal position, and additional off-normal contacts included in the circuit of said supervisory apparatus and opened responsive to said switch attaining its normal position.

15. In an automatic telephone system, a connector switch arranged to extend connections to party lines, a party selector associated with said switch and having two wipers,

code signalling conductors differently connected to the bank contacts of said two wipers, means effective after said connector has been set upon the terminals of a called party line and after said party selector has been positioned for placing the signalling of the line under the control of the first of said two wipers of the party selector, and means in said connector effective after the line has been signalled depending upon the setting of the first wiper for substituting the second wiper of the party selector for the first wiper.

16. In a telephone system, a connector switch having access to party lines, a code selector associated with said connector switch, said code selector having two wipers, means for positioning said wipers in accordance with the code assigned to the desired party on a called party line, a ringing relay and a reversing relay in said connector, a code signalling device and means for operating it to control said ringing relay through the first wiper of the code selector, and means for thereupon operating said reversing relay to shift the ringing relay under the control of the second wiper of the code selector instead of the first.

In witness whereof, I hereunto subscribe my name this 23d day of November, A. D. 1929.

NORMAN H. SAUNDERS.

In witness whereof, I hereunto subscribe my name this 23d day of November, A. D. 1929.
